LOCOMOTIVE

Filed July 27, 1927

UNITED STATES PATENT OFFICE

EUGENE L. SCHELLENS, OF MILLBURN, NEW JERSEY, AND CHRISTOPHER A. SCHELLENS, OF MARBLEHEAD, MASSACHUSETTS, ASSIGNEES TO C-S ENGINEERING COMPANY, OF JERSEY CITY, NEW JERSEY, A CORPORATION OF DELAWARE

LOCOMOTIVE

Application filed July 27, 1927. Serial No. 208,796.

This invention relates to locomotives, particularly to boiler feed mechanisms therefor.

The primary object of the invention is to provide means for venting any air which may be present in the feed water pump or its intake or discharge pipes. Such air forms in pockets, at times, particularly when the locomotive is standing idle, with the result that the suction action of the pump is impaired. Sometimes the entire feed water system becomes filled with air with the result that the pump is rendered entirely ineffective. This difficulty is encountered to a certain extent with all types of feed water pumps but particularly with the centrifugal type as the pumping elements of a centrifugal pump frequently require priming fluid for starting.

Lack of suction also results when the boiler check valve develops leakage. This leakage at times, is sufficient to fill the feed system with steam and drive the water all the way back to the tender. We also aim to overcome difficulties resulting from such leakage.

Venting valves have sometimes been applied to feed water systems but these have always required manual operation. According to the present invention we provide a venting system which requires no attention and which is entirely automatic in operation.

How the foregoing together with other objects and advantages are obtained will be clear from the following description considered in connection with the accompanying drawing which illustrates a preferred embodiment of the invention and in which

Fig. 1 is a somewhat diagrammatic fragmentary side view of an engine and tender with a pump of the centrifugal type, with its intake and delivery pipes, and the venting system of the present invention applied thereto; and

Fig. 2 is a view on an enlarged scale and

in vertical section of the intake immediately adjacent the pump.

Referring now to the drawing, the reference letter A indicates the locomotive which is shown in outline only in order to avoid complication in the drawing. The tender is indicated at B, also only in outlines.

The pump 3 may be mounted on the locomotive in any suitable location and manner. The pipe 4 communicates at one end with the tender tank, through the flexible connection 5 and at its other end with the suction side of the pump, through the strainer chamber 6 which is shown in detail in Fig. 2. A motor 7 supplied with fluid pressure through the pipe 8 serves to drive the pump 3. Water is delivered from the pump 3 to the boiler or feed water heater through the connections 9.

The venting system comprises a pipe 13 communicating at one end with the discharge line 9 and at the other end with a vent 12 which is located at a point well above the high water level in the tender. The connection 13 is provided with a valve 14 of any suitable type which is adapted to close when the pump is in operation, i. e. when there is water pressure in pipe 13. This valve may take the form of a check valve, such, for example, as an inverted ball check valve, and is preferably located just below the vent 12 above the high water level in the tender.

If desired, a pipe 10 may be provided to vent air from the suction side of the pump 3. This pipe may communicate with the vent 12 at one end and with the chamber 6 at the tender side of the screen 11 in said chamber. (See Fig. 2.)

A cap 15 may be provided on the chamber 6 for purposes of removing dirt and cleaning or renewing the screen 11.

When the pump is standing idle the valve 14 remains open and any air or steam which may have worked its way into the feed water pumping system passes upwardly through the valve 14 and out of the vent 12.

Thus the pump will always remain full of water and ready for operation.

In cases where the pipe 10 is also applied, any air which may become pocketed on the 5 tender side of the screen 11 will pass directly to the vent 12 through this pipe 10.

We claim:—

1. In a locomotive having a boiler with its feed check valve and a tank, a feed water system including a heater, a centrifugal pump positioned for gravity feed from said tank, said pump having connections to said boiler and heater, whereby it is subject to possible leak or influx of steam and air from both, vent means for the pump in communication with the discharge side of the pump, and means for closing off said communication upon operation of the pump. 15
2. In a locomotive having a boiler with its feed check valve and a tank, a feed water system including a feed water heater in the tank, a centrifugal pump positioned for gravity feed from said tank heater, a pipe connection from the tank heater to the suction side of the pump, and a pipe connection from the discharge side of said pump leading to the boiler, said pump working against the boiler pressure, and vent means for the pump having an outlet above the high water 25 level of the tank, both of said pipe connections being in communication with said vent means whereby the pump is relieved of steam and air working forwardly thereto from the heater or rearwardly thereto from the boiler. 30
3. In a locomotive having a boiler with its feed check valve and a tank, a feed water system including a feed water heater in the tank, a centrifugal pump positioned for gravity feed from said tank heater, a pipe connection from the tank heater to the suction side of the pump, and a pipe connection from the discharge side of said pump leading to the boiler, said pump working against the boiler pressure, and vent means for the 40 pump having an outlet above the high water level of the tank, both of said pipe connections being in communication with said vent means whereby the pump is relieved of steam and air working forwardly thereto from the heater or rearwardly thereto from the boiler, and means automatically operable by the discharge water of the pump for shutting off communication between the boiler pipe connection and the vent. 45
4. In combination, with a locomotive having a boiler with its feed check valve; a water supply tank; a feed water system including a water heater; a rotative pumping device positioned below the normal low water 50 level of the said tank; piping connecting said rotative pumping device, the heater and the boiler, and including a line gravity-fed from the supply tank, whereby the pumping device is subject to possible leak or influx, 55 from boiler, heater and tank, of gases such

as steam, air and the like; venting means for said rotary pumping device having means of communication therewith and operative to vent such gases as may collect therein by influx from either the discharge or the suction side thereof, all of said parts being so arranged that upon operation of the pumping device an automatic seal is formed as against appreciable loss through the venting means of the water being delivered by the 75 pumping device.

In testimony whereof we have hereunto signed our names.
